UNITED STATES PATENT OFFICE

2,519,372

PICKER STICK STOP MECHANISM

George Hiram Hufferd, Shaker Heights, Ohio, assignor to Houdaille-Hershey Corporation, Detroit, Mich., a corporation of Michigan

Application July 9, 1948, Serial No. 37,952

12 Claims. (Cl. 139—149)

1

This invention relates to an improved mechanism for controlling the movements of a picker stick of a loom, and particularly to a stop mechanism for accurately positioning the picker stick in its shuttle catching position.

In my copending applications, Serial Nos. 37,950 and 37,951, filed concurrently herewith, there is described and claimed an improved mechanism for controlling the cyclic movements of the picker stick of a loom, characterized by the suspension of the picker stick by a plurality of pivoted links which are in turn mounted upon a primary bracket element secured to the rock shaft of the loom. A mechanism of this type is particularly adaptable to hydraulic checking of the excess energy imparted to the picker stick in its normal cycle of operation. The hydraulic checking arrangement described in my above referred to copending application permits the complete elimination of the check strap arrangements heretofore employed in looms and accomplishes the necessary checking of the movements of the picker stick with a substantial reduction in impact forces upon the various elements of the picker stick linkage together with a much higher degree of uniformity in the checking action than has been heretofore possible.

Those skilled in the art will recognize that the conventional check strap performed another function in addition to checking the excess energy movements of the picker stick. This additional function was the positioning of the picker stick in its intermediate or shuttle catching position. After the shuttle is thrown and the inward movement of the picker stick is properly checked, it was customary to return the picker stick to its intermediate or shuttle catching position through the bias exerted by a suitable spring, generally a torsion spring, which operates on the lower portions of the picker stick. The check strap was so arranged as to be engaged by the picker stick as it is returned outwardly by the torsion spring and thus stop the picker stick at the proper position for catching the shuttle when it is thrown back from the other side of the loom. With the complete elimination of the checking functions of the check strap accomplished by the utilization of an hydraulic check arrangement in accordance with the disclosures of my above referred to copending applications, it is therefore necessary to provide some means for accurately repositioning the picker stick at its intermediate or shuttle catching position.

Accordingly, it is an object of this invention to provide an approved mechanism for control of the

2

movements of a picker stick of a loom, and particularly an improved stop mechanism for positioning the picker stick in its intermediate, shuttle catching position.

5 A further object of this invention is to provide a stop mechanism for a hydraulically controlled picker stick linkage to accurately and uniformly position the picker stick of a loom in its intermediate, shuttle catching position immediately following the checking of the inward, or shuttle throwing stroke of the picker stick.

Still another object of this invention is to provide an improved stop mechanism for picker stick linkages embodying the utilization of a resilient 15 latch element carried by one link member of the picker stick linkage which cooperates with a stop member carried by another linkage member, and the proportioning of the resilient latch member in such manner as to effect the retention of the picker stick in the desired intermediate, shuttle catching position against the bias of the return spring, but to release the picker stick under the forces developed by the shuttle impact thereon, and to avoid interference with any other portion 20 of the cyclic movements of the picker stick.

Still another object of this invention is to provide a stop mechanism for a picker stick of a loom characterized by simplicity of construction and ease of manufacture, and which mechanism may 25 be conveniently assembled to new or existing looms.

The specific nature of this invention, as well as other objects and advantages thereof will become apparent to those skilled in the art from the following detailed description taken in conjunction with the annexed sheets of drawings, on which, by way of preferred example only, are shown two modifications of the invention.

On the drawings:

40 Figure 1 is a side elevational view of an hydraulically controlled picker stick linkage incorporating a stop mechanism embodying this invention, showing the position of the components when the picker stick lies adjacent its innermost position;

45 Figure 2 is a view similar to Figure 1 but illustrating the position of the components when the picker stick is retained by the stop mechanism in its intermediate, shuttle catching position;

50 Figure 3 is an enlarged scale, top elevational view of the stop link or arm incorporated in the picker stick linkage of Figure 1;

55 Figure 4 is a side elevational view of a picker stick linkage incorporating a modified stop mechanism embodying this invention;

Figure 5 is a perspective view of the stop link or arm incorporated in the mechanism of Figure 4; and

Figure 6 is an enlarged scale, partial sectional view taken on the plane VI-VI of Figure 4.

As shown on the drawings:

Referring to Figure 1, the numeral 10 indicates the rock shaft of a loom while the numeral 11 indicates a conventional picker stick. Picker stick 11 is supported for oscillating movements with respect to the rock shaft 10 by a linkage which controls the movement of the picker stick so that the top end (not shown) of the stick traverses a substantially horizontal, straight line path. Such linkage, which is described in detail in my copending application, Serial No. 37,951, filed concurrently herewith, may comprise a primary bracket 12, rigidly secured to the rock shaft 10, and a secondary bracket 13 which is connected to primary bracket 12 by a pair of pivoted links 14 and 15. The location of the pivot points of links 14 and 15, as well as the relative dimensions of such links are selected in the manner described in my above referred to copending application, so that the picker stick 11 can move only in a path which will result in the upper end of the stick moving along the lay (not shown) in a substantially horizontal, straight line path.

The primary bracket 12 defines three spaced pivoted bearings, 12a, 12b and 12c respectively. Pivot bearing 12a is located in slightly depending relationship with respect to rock shaft 10 and provides pivotal support for one end of the link 15. Pivot bearing 12a is preferably of bifurcated construction and thus surrounds the end of link 15.

Pivot bearing 12b is also of bifurcated construction and is located directly above the end of rock shaft 10 and provides pivotal support for the cylinder element 21 of an hydraulic check unit 20. The hydraulic check unit 20 is preferably of the type described in detail and claimed in my copending application Serial No. 37,950, filed concurrently herewith, and will therefore not be further described.

Lastly, pivot bearing 12c is defined by a yoke-shaped portion 12d of primary bracket 12 and such pivot bearing is disposed in generally triangularly spaced relationship with respect to the pivot bearings 12a and 12b and pivotally journals one end of the link 14. The secondary bracket 13 is of generally reversed E-shaped configuration and may be conveniently formed by riveted assemblage of two half parts, as indicated by rivets 13e. The backslide of the upright portion of bracket 13 is suitably apertured, as indicated at 13d, so as to conform to and snugly partially surround the bottom portion of the picker stick 11. Picker stick 11 is rigidly clamped in recess 13d by a plurality of U-shaped clamps 17 which are secured to secondary bracket 13 by bolts 17a.

Secondary bracket 13 likewise defines three pivot bearings which are respectively located in the ends of its arm portions. Thus, a bifurcated pivot bearing 13a is formed in the end of the lowermost arm portion and pivotally journals the other end of link 15. A bifurcated pivot bearing 13b is mounted in the end of the top arm portion and pivotally journals the end of a piston rod 26 of the hydraulic check unit 20. Lastly, a pivot bearing 13c is provided in the end of the intermediate arm and pivotally journals the other ends of links 14. All of the pivot bearings heretofore mentioned embody suitable pivot pins and grease fittings 9.

It will be understood by those skilled in the art that conventional mechanism will be provided for producing the required cyclic movements of the picker stick 11. For example, a power driven lug strap (not shown) having a looped portion surrounding the intermediate portion of picker stick 11 may be provided to impart the high acceleration inward movement to the picker stick which is required for throwing of the shuttle. 5 In such throwing movement, the picker stick 11 is shifted from its extreme outward position to its extreme inward position. After the shuttle is thrown, the inward movement of the picker stick 11 is checked by the hydraulic unit 20 and the picker stick 11 is brought to rest approximately in the position indicated in Figure 1 of the drawings. As is well understood, a substantially identical arrangement of a picker stick and its associated control mechanism is provided on the other 10 side of the loom for catching and throwing the shuttle.

It is then necessary that the picker stick be shifted outwardly to an intermediate position wherein it will catch the shuttle when the shuttle is thrown back from the other side of the loom. In accordance with this invention, a torsion spring 40 is provided which operates between any 15 two relatively movable parts of the picker stick control linkage, for example operating between secondary bracket 13 and link 15, and is arranged to urge the picker stick 11 outwardly. To interrupt such outward movement of the picker stick 11 when the top of the stick is positioned at the proper shuttle catching position, this invention provides a stop mechanism indicated generally by the numeral 50. Such mechanism comprises a fixed stop pin 51 which may be mounted in any 20 convenient element of the control linkage, such as the link 15 which has an integral boss portion 15a formed thereon for receiving the stop pin 51. To cooperate with the stop pin 51, a stop link or arm 52 is provided, which has one end 52a thereof pivotally journaled to another member 25 of the picker stick control linkage which moves relative to the link 15 during the cyclic movements of the picker stick. Such member may conveniently comprise the secondary bracket 13. In such case, the end 52a of the stop link 52 is pivotally journaled on a pin 53 which is pressed into the secondary bracket 13. The stop link 52 is provided with a resilient latch element 53 30 which may comprise a leaf spring member having one end portion 53a secured to the stop link 52 by a clamp 55 and the other end portion bifurcated as indicated at 53b to provide added resilience. The free ends of such bifurcated portions are angularly bent into a V-shape, as indicated at 53c, so as to provide an inclined latching surface to engage with the stop pin 51 when 35 the picker stick 11 is moved to its proper shuttle catching position by the spring 40.

To permit the convenient adjustment of the latch element 53 with respect to the stop pin 51, such latch element may be adjustably secured in 40 any one of a plurality of positions along the stop link 52 by having a slotted portion 53d receiving a clamping bolt 54 and being clamped in assemblage on the stop link 52 by the clamping plate 55 which is secured thereon by the bolt 54. The adjacent surface of the stop link 52 may be provided with longitudinally spaced, transverse grooves 52b which respectively accommodate downturned end portions 53e of the leaf spring 45 element 53 and thus permit a convenient indexing 50

of the position of the leaf spring element 53 along the stop link 52.

To adjust the effective tension with which the leaf spring latching element 53 resists displacement past the stop pin 51, the clamping plate 55 is formed with integral extensions 55a which respectively overlie the secured end portions of the bifurcated portion 53b of the leaf spring element 53. An adjusting screw 56 is then mounted in each overhanging portion 55a and tightening of the screw 56 will urge the bifurcated portion 53b more tightly into engagement with the stop pin 51, and hence increase the force necessary to overcome the latching action on pin 51 produced by the resilient latch 53.

Suitable adjustments are made so that the resilient latch 53 is effective to interrupt the outward movement of the picker stick 11 produced by the torsion spring 40 and to stop the picker stick 11 at the proper position to catch the shuttle. However, the retaining effect on the picker stick exerted by the leaf spring latching element 53 is readily overcome by the forces produced in the linkage by the impact of the shuttle on the picker stick 11. Such action produces a high acceleration outward displacement of the picker stick 11, which causes the inclined surfaces 53c of the resilient latch element 53 to ride up over the stop pin 51. However, before the bifurcated ends of the resilient latch 53 ride off the stop pin 52, the hydraulic check unit 20 has operated to smoothly check the outward movement of the picker stick 11 and stop the picker stick 11 with the shuttle in the proper position in the shuttle box (not shown). Hence the entire mechanism is again ready for the inward, shuttle throwing stroke of the picker stick 11.

In the modification of this invention illustrated in Figures 4 through 6 of the drawings, a slightly different design of the hydraulic cylinder unit and the primary bracket is employed which is described in detail and claimed in my copending application Serial No. 37,950 filed July 9, 1948. So far as the operation of the stop mechanism is concerned, however, the modified primary bracket 12' and the modified check unit 20' function in an entirely identical manner to similar components heretofore described in connection with the modifications of Figures 1 to 3. With these exceptions, the picker stick control linkage is otherwise identical, embodying secondary brackets 13, links 14 and 15 interconnecting the primary and secondary brackets and the torsion spring 40 which normally urges the picker stick 11 toward its outermost position.

The stop mechanism 60, however, is of somewhat different construction. The stop pin 61 is now mounted in a bifurcated portion 12'e of the primary bracket 12' which also defines the lowermost pivot bearing 12'a. A stop link or arm 62 is provided to cooperate with the stop pin 61, but in this modification, such link comprises an elongated strip of resilient metal which is bent upon itself to provide parallel arm portions 62a and 62b which are in abutment over the greater portion of the length of the stop link 62. The bight portion 62c in this stop link is formed in a generally cylindrical configuration and this portion receives a cylindrically shaped, eccentric portion 63a of an eccentric pivot 63 which is mounted in transverse relationship in the secondary bracket 13. Eccentric pivot 63 also includes a head portion 63b which abuts against the side face of secondary bracket 13 and a reduced diameter shank portion 63c concentric with the head portion 63a

which projects through the opposite wall of secondary bracket 13 and is threaded to receive a locking nut 64 thereon. Hence, it is apparent that the angular position of the eccentric pivot 63 may be selectively adjusted by turning of this member relative to the secondary bracket 13 and the pivot 63 may be locked in any desired angular position by tightening of the nut 64. In this manner, the effective longitudinal position of the stop link 62 relative to the stop pin 61 may be conveniently varied.

The two arms 62a and 62b of the stop links 62 are clamped in abutting relationship by a U-clamp 65 which is tightened by a bolt and nut 66.

15 Adjacent the free ends of the arm portions 62a and 62b, such arm portions are outwardly displaced as indicated at 62d and 62e respectively so as to permit these portions to surround and abut the stop pin 61. The extreme end portions 62f and 62g are in abutment and inclined juncture portions 62h and 62j are thus defined between portions 62d, 62e and 62f, 62g respectively. Inclined portions 62h and 62j respectively function as abutment surfaces and engage the stop pin 61 to retain the picker stick 11 in the proper intermediate, shuttle catching position against the bias of torsion spring 40.

When the shuttle strikes the top end of the picker stick 11, the resulting impact forces are sufficient to spread the extreme ends 62f and 62g of the stop link 62 and permits such ends to ride up upon the stop pin 61. Hence the primary checking of the outward movement of the picker stick 11 after the shuttle impact will again be accomplished by the hydraulic check unit 20'.

In both modifications of this invention, it should be noted that the stop mechanism does not interfere in any manner with the operation of the picker stick control linkage during other portions of the cycle of movement of the picker stick. During the forward throw of the picker stick 11, the stop mechanism is ineffective and exerts only a light frictional drag between the stop link and the cooperating stop pin. However, each time that the picker stick 11 tends to return to its outermost position under the bias of the torsion spring 40, the stop mechanism is effective to interrupt the movement of the picker stick 11 in exactly the proper position for catching the shuttle on the return throw. Of course, additional effort is required to overcome the latching action of the stop mechanism after the shuttle impact, but this additional effort is very desirable in that it helps to absorb the excessive impact forces imparted to the linkage by the impact of the returning shuttle.

From the foregoing description it is apparent that this invention provides an improved stop mechanism for picker stick linkages, and particularly for linkages of the hydraulically controlled type. In both modifications of the invention, convenient adjustment of the effective location of the shuttle catching position of the picker may be effected in a minimum time, there-by permitting the loom to be periodically adjusted to optimum operating conditions without incurring any substantial shut-down time to effect such adjustment. Furthermore, the stop mechanisms herein described may be conveniently and economically manufactured by large quantity, low cost production methods.

It will, of course, be understood that various details of construction may be modified through a wide range without departing from the principles of this invention and it is, therefore, not

the purpose to limit the patent granted hereon otherwise than necessitated by the scope of the appended claims.

I claim as my invention:

1. In a picker stick linkage for a loom, a first linkage member movable with the picker stick, a second linkage member having a variable displacement relative to said first linkage member as the picker stick moves, a spring urging the picker stick to its extreme outward position, a stop secured to one of said linkage members, an arm secured to the other of said linkage members and extending adjacent said stop, said arm having yieldable latch means thereon engageable with said stop to retain the picker stick at its shuttle catching, intermediate position against the bias of said spring, said latch means being constructed to disengage from said stop under the force of shuttle impact on the picker stick.

2. In a picker stick linkage for a loom, a first linkage member movable with the picker stick, a second linkage member having a variable displacement relative to said first linkage member as the picker stick moves, a spring urging the picker stick to its extreme outward position, a stop secured to one of said linkage members, an arm secured to the other of said linkage members and extending adjacent said stop, yieldable latch means on said arm engageable with said stop to retain the picker stick at its shuttle catching, intermediate position against the bias of said spring, said latch means being constructed to disengage from said stop under the force of shuttle impact on the picker stick, and means for varying the effective position of said latch means relative to said stop, thereby permitting adjustment of the shuttle catching position of the picker stick.

3. In a picker stick linkage for a loom, a first linkage member movable with the picker stick, a second linkage member having a variable displacement relative to said first linkage member as the picker stick moves, a spring urging the picker stick to its extreme outward position, a stop secured to one of said linkage members, a stop link, means for pivotally mounting said stop link to the other of said members, said last mentioned means including an eccentric element angularly adjustable to shift the position of said stop link relative to said stop, and yieldable latch means on said stop link engageable with said stop to retain the picker stick at its shuttle catching, intermediate position against the bias of said spring, said latch means being constructed to disengage from said stop under the force of shuttle impact on the picker stick.

4. In a picker stick linkage for a loom having a primary bracket for attachment to a picker stick and a secondary bracket for attachment to the loom, links interconnecting said brackets to control the movements of the picker stick relative to the loom and a spring urging the picker stick toward one extreme position of relative displacement, the improvements comprising a stop mounted on one of said brackets, an arm pivotally secured to the other of said brackets and lying adjacent said stop, and yieldable latch means on said arm engageable with said stop to position said bracket in an intermediate position against the bias of said spring, said intermediate position of said brackets corresponding to the shuttle catching position of the picker stick, said latch means being constructed to yieldingly disengage from said stop by the force resulting from the shuttle impact on the picker stick.

5. In a picker stick linkage for a loom, a first linkage member movable with the picker stick, a second linkage member having a variable displacement relative to said first linkage member as the picker stick moves, a spring urging the picker stick to its extreme outward position, a stop secured to one of said linkage members, a stop link secured to the other of said linkage members and extending adjacent said stop, said stop link including a leaf spring latch element having an inclined surface portion engageable with said stop to retain the picker stick against the bias of said spring in an intermediate, shuttle catching position, said latch element being proportioned to disengage from said stop by the shuttle impact force on the picker stick.

6. In a picker stick linkage for a loom, a first linkage member movable with the picker stick, a second linkage member having a variable displacement relative to said first linkage member as the picker stick moves, a spring urging the picker stick to its extreme outward position, a stop secured to one of said linkage members, a stop link secured to the other of said linkage members and extending adjacent said stop, said stop link including a leaf spring latch element having an inclined portion engageable with said stop to retain the picker stick against the bias of said spring in an intermediate, shuttle catching position, said latch element being proportioned to disengage from said stop by the shuttle impact force on the picker stick, and means for varying the effective position of said latch means relative to said stop, thereby permitting adjustment of the shuttle catching position of the picker stick.

7. In a picker stick linkage for a loom, a first linkage member movable with the picker stick, a second linkage member having a variable displacement relative to said first linkage member as the picker stick moves, a spring urging the picker stick to its extreme outward position, a stop secured to one of said linkage members, a stop link secured to the other of said linkage members and extending adjacent said stop, a leaf spring latch element, means for adjustably securing one end of said latch element to said stop link in any selected one of a plurality of positions along said stop link, the free end of said latch element being angularly disposed and engageable with said stop in latching relation, thereby retaining the picker stick in an intermediate, shuttle catching position against the bias of said spring, and said leaf spring element being constructed to release from said stop under force of shuttle impact on the picker stick.

8. In a picker stick linkage for a loom, a first linkage member movable with the picker stick, a second linkage member having a variable displacement relative to said first linkage member as the picker stick moves, a spring urging the picker stick to its extreme outward position, a stop pin projecting from one of said linkage members, a stop link comprising a folded strip of spring metal, said stop link having a bight portion defining a pivot bearing, means cooperating with said pivot bearing for pivotally securing said stop link to the other of said linkage members, at least a portion of said stop link being disposed in surrounding relation to said stop pin and defining an angularly inclined surface engageable with said stop pin in latching relation, thereby retaining the picker stick in an intermediate, shuttle catching position against the bias of said spring, said stop link being constructed to

yieldingly disengage from said stop pin by the shuttle impact force on the picker stick.

9. The combination defined in claim 8 wherein said means for pivotally securing said pivot bore of the stop link to said other linkage member comprises an eccentric pin, and means for selectively angularly positioning said pin, thereby adjusting said stop link relative to said stop pin and varying the shuttle contact position of the picker stick.

10. A stop mechanism for a shuttle loom of the type having a picker stick, a picker stick control linkage and biasing means to urge the picker stick towards an extreme outward position, comprising, a stop on one linkage element, an arm connected to another linkage element and constructed to be cooperable with said stop to retain the picker stick at an intermediate shuttle-catching position against the outwardly directed bias.

11. A stop mechanism for a shuttle loom of the type having a picker stick and a picker stick control linkage normally biased to place the picker stick at an extreme outward position, comprising, an arm connected to a relatively movable linkage member, said arm defining means cooperable with another linkage member to retain the picker stick at an intermediate shuttle-catching position against the outwardly directed

bias, said means on said arm being constructed to permit movement of the picker stick control linkage and the picker stick under the force of a shuttle impact.

5 12. A stop mechanism for a picker stick linkage in a shuttle loom having one linkage member movable with a picker stick and another linkage member variably displaceable relative to the other linkage member as the picker stick moves, 10 comprising an arm connectable to one of said linkage members, yieldable latch means on said arm cooperable with the other of said linkage members to retain the picker stick at a shuttle-catching intermediate position and means for 15 varying the effective position of said latch means relative to the linkage members associated therewith, whereby adjustment of the shuttle-catching position of the picker stick may be made.
